UNITED STATES PATENT OFFICE.

WARD T. SIMPSON, OF GRAND RAPIDS, MICHIGAN, ASSIGNOR TO ALBERT G. DICKIN-
SON, OF GRAND RAPIDS, MICHIGAN.

CARBURETOR.

Application filed July 18, 1923, Serial No. 651,748. Renewed March 26, 1927.

This invention relates to carburetors and is particularly concerned with various improvements and simplifications in structure in carburetors wherein the fuel supply is automatically kept at a predetermined level, 5 suction of the engine with which the carburetor is used lowering the air pressure in the carburetor bowl and the greater air pressure in the main supply tank for the fuel causing fuel to flow to the said bowl. The invention 10 consists in various novel constructions and organizations of elements for the production of a simple and effective carburetor of this type as will more fully appear as under- 15 standing of the invention is had from the following description taken in connection with the accompanying drawing, in which,

Fig. 1 is a vertical longitudinal section through the carburetor.

Fig. 2 is a vertical transverse section 20 through the fuel supply tank.

Fig. 3 is a horizontal section through the upper end portion of the manually operable control member for the supply of fuel from 25 the carburetor bowl to the engine, and this section is taken in the horizontal plane of the port 42, Fig. 1.

Fig. 4 is a like section through the lower end portion thereof. This section is taken 30 along the horizontal plane of the port 49 and thence along the plane of the passage 48.

Like reference characters refer to like parts in the different figures of the drawing.

In the carburetor construction, a single 35 casting is made included in which is a fuel bowl having a bottom 1, an outer side 2, a top 3 and an inner vertical side 4 extending only part of the height of the side 2 and from which projects an outwardly extending 40 air inlet 5. At the upper side of the air inlet and near the side 2, an upwardly extending vertical sleeve 6 is made which lies within an outer sleeve 7 also cast integral with the rest of the casting and which at its vertical side 8 joining with the top 3 is thickened, 45 as shown the purpose of which will appear later. At the upper end of the vertical sleeve 7 it is reduced in size, as at 9, making a passage 10 of less diameter than the inner 50 diameter of the sleeve, the usual throttle valve 11 being mounted in the passage 10, a short distance above the chamber 12 located above the upper end of the sleeve 6 and which is connected by a passage 13 around 55 the sleeve 6 with the interior of the bowl.

In the upper side 3 of the bowl an opening is made which is closed by a plate 14. Integral with the plate is a chamber 15 into which the fuel first comes from the main supply tank. A plug 16 is threaded through 60 the bottom of the chamber provided by the plate 14 and has a vertical opening 17 therethrough. Into the lower end of the opening 17 the upper pointed end of a rod 18 is adapted to seat, the same being pivotally 65 connected at its lower end to a bar 19, one end of which carries a float 20 and the other end being pivotally mounted at 21 to a relatively fixed bar 22 depending from the 70 plate 14.

In the upper side of the chamber 15 a plug 23 is secured on the under side of which a screen 24 is secured. A coupling 25 attached to the plug has the main feed line pipe 26 for the fuel secured thereto, said pipe connecting with a similar pipe 26' which is secured by a coupling 27 to a member 28 at the upper side of the fuel tank 29, into which from the coupling 27 a vertical pipe 30 extends nearly to the bottom of the tank 80 and in which at a plurality of spaced apart points small openings 32 are made in its sides, the uppermost one being above the highest level of fuel in the tank approximately one and one-half inches, the next approximately four inches below the uppermost opening and the lowermost and others which may be used in larger tanks approximately three inches apart from the adjacent 85 openings. A vent tube to the outer atmosphere of relatively large diameter is connected with the member 28 as shown at 31.

Bores 33 and 34 are made in the lower and upper sides 1 and 3 of the carburetor bowl adjacent the inner side thereof and a rod 35 95 passes through the same and is rotatably mounted therein, having an enlarged head 36 at its upper end passing into the bore 34 and at its lower end extending into an opening made through the bore 33. This rod is bored from its lower end nearly through the head thereof, making a longitudinal passage 37 therein. A spring 38 presses against the upper end of the head 36 to hold the rod in lower position. An arm 39 extends from the head 36 and has an operating rod 40 connected therewith which may be manually operated for changing the position of the member 35. An adjustable stop 41 limits the movement of the arm 39 in one direction. 100

- An opening 42 is made laterally through the head and communicates with the passage 37 in member 35 and when the said member is turned to one position, said opening 42 comes into conjunction with a passage 43 made in the thicker side 8 of the sleeve 7, leading to immediately above the throttle 11 when the same is in substantially closed position. Openings 44 are made through the sides of the member 35 below the fuel level in the bowl and a plug 45 is located in the passage 37 below said openings. Below the plug a slot 46 is cut in a side of the member 35 and in the same plane with the slot a groove 47 is made in the outer side of the member 35, gradually decreasing in depth, as shown in Fig. 4, as it extends away from the slot. The groove extends substantially one quarter of the way around the member 35 so as to make a communicating passage between said slot 36 and a passage 48 which leads away from the member. Fuel is carried from the bowl through an opening 49 made in the wall of the bore 33 so that the openings and passages in the member 35 below the plug 44 are filled with fuel at all times. A stop plug or disk 50 fills the lower end of the opening in the bore 33, preventing loss of fuel.
- In the under side of the air inlet 5 a relatively large opening is made through which the nozzle member 51 may be passed upwardly, it having an enlarged lower end covering the opening, as indicated at 52 and which is held in place by the set screw 53, bringing the opening or passage 54 in the nozzle member into conjunction with the passage 48 for the fuel. This passage 54 joins with a vertical passage 54^a in the nozzle member into which the lower end of a tube 55 extends, the latter at its upper end being slightly enlarged and flared outwardly, as shown at 55^a. The upper end of the tube 55 extends partly through a sleeve 56 tapering slightly upward on its inner sides and which is received in the upper end of an enlarged passage 57 made vertically in the upper extension 58 of the nozzle member 51, said extension enlarging downwardly and outwardly at its lower portion at 59 thereby providing a seat for the lower end of the valve, hereafter described, as mounted in the sleeve 6. At one side a passage 60 is made through the enlarged part 59 upwardly and inwardly to the vertical passage 57, and an adjusting screw 61 is threaded through the lower enlargement 52 and at its upper end passes into the passage 60 whereby the same may be enlarged or restricted at will.
- A valve 62 in the form of a vertical cylinder is slidably mounted in the sleeve 6, being provided with a flange at its lower end, the corner 63 at the lower side of the flange and the inner sides of the valve being sharp so that in a relatively short time it cuts or wears a seat against the upper side of the
- part 59 due to the impinging of the said corner against the curved outer sides of the part 59. The lower portion of the valve is reduced in thickness, as at 64, for a portion of its height, thereby providing an annular recess between the valve and the inner walls of the sleeve 6, as at 65, for a purpose to be later set forth.
- The corner at 63 on the valve 62 in a short time wears a seat in the upper side of the nozzle member so that the contact is from one-fifth to one-third of the area of the lifting area of the air against the under end of the valve. The valve, accordingly has a tendency to cling to the seat slightly with the production of a greater vacuum in the chamber 12 than would be the case if the area of the contact between the valve and nozzle was reduced to a minimum, as in a knife-edge contact. The increase in vacuum causes a greater flow of air through the passage 60 and past the fuel nozzle with the setting up of a greater injector action on the fuel causing a greater flow of fuel. This is an important feature of the invention, there being furnished a richer fuel mixture when the engine is at idle.
- It will be noted that the chamber 12 is located directly under the throttle valve 11 and as far above the nozzle as possible. The air passing under the lower end of valve 62 passes by the throttle valve in its major portion, but other portions thereof strike against the upper sides of the chamber 12 at the sides of the opening 10, setting up reverse eddies which have a tendency to counteract the production of too high a vacuum in the float chamber, connected as it is by passage 13 directly with the mixing chamber at 12. As nearly as possible the pressure in the mixing chamber and the float chamber is kept approximately equal, the injector action of the air rushing past the nozzle of the fuel tube 55 causing the fuel to be drawn into the current of air to mix there. The fuel in the normal running of the engine passes through the opening 49 and groove 47 to the passage 48 and thence to the tube 55, and if the amount of fuel required is to be increased, it is done by actuating the operating rod 40 so as to make a larger passage through the groove 47 by turning member 35, as is obvious.
- If a very rich mixture is desired, as in starting, the rod 40 is operated so as to turn the member 35 a quarter turn to bring opening 42 and passage 43 into conjunction, fuel being drawn directly from the bowl to the mixing chamber above the throttle 11 which is nearly closed. The air rushing by the throttle breaks up and mixes with the fuel which in a rich mixture passes to the engine. In this operation, a limited amount of air passes through the port opening 35^a to mix with and lighten the column of fuel passing

through the passage 43 and facilitate the mixing with additional air passing by the valve 11. This port opening also neutralizes the pressure in the passage 37 with the pressure in the float chamber when the member 35 is in operative running position.

The float assembly described is a complete unit in itself capable of attachment or removal as a unit for repair, inspection or replacement by a new assembly. Its manufacture, assembly and attachment is simple and relatively inexpensive. The construction as a whole is practical in all respects and has so proved in practice.

15 I claim:

1. In a carburetor, a fuel bowl, a nozzle member, a conduit for fuel from the lower part of the bowl through the nozzle member, a casing enclosing a mixing chamber above the nozzle member, a stationary guide sleeve around the upper portion of the nozzle member and below the mixing chamber, and a sleeve valve slidably mounted in the guide sleeve and tending to bear through gravity at its lower end against the nozzle member, said member being enlarged outwardly between its ends to form a rest for said sleeve valve, said valve at its lower end being reduced in thickness by cutting away a portion at its outer sides which extends to a point above the lower end of the guide sleeve when the valve is in its lowermost position, substantially as and for the purposes described.

35 2. In a carburetor, a mixing chamber enclosed in a suitable casing, a stationary guide sleeve located below the chamber and open at its ends, a nozzle member having a fuel carrying passage therethrough extending into the guide sleeve, said member below the lower end of the sleeve having its sides curved downwardly and outwardly to make an enlargement of the nozzle member, and a sleeve valve slidably mounted in the guide sleeve with its lower end adapted to bear against the outwardly and downwardly curved sides of the nozzle member when in lower position, said valve at its lower end having a sharp corner formed between its inner sides and the lower end of the valve to contact with and make a seat where contact is made with the nozzle member, as described.

50 3. In a carburetor, a fuel bowl, a mixing

chamber having communication with the upper part of the fuel bowl, a nozzle member having its upper portion bored lengthwise for a part of the length of the nozzle member and having a lateral passage to the side at the lower end of the opening bored in the nozzle member, a member adjustably mounted on the nozzle member and extending into said lateral passage, a tube located lengthwise of the opening bored in the nozzle member, a sleeve around the upper end of the tube and extending above the same, a conduit for fuel from the fuel bowl to said tube, means for manually controlling the amount of fuel passing to the tube, a guide sleeve open at both ends located around the upper part of the nozzle member and below the mixing chamber, and a cylindrical valve slidably mounted in the guide sleeve and adapted to rest in its lowermost position on a lateral enlargement of the nozzle member at a point above the lateral passage made in the nozzle member, substantially as described.

4. In a carburetor, a casing including a fuel bowl, a mixing chamber having an outlet thereto and a throttle valve in said outlet above the mixing chamber, there being an open passage between the fuel bowl and mixing chamber, a nozzle member having a fuel passage therethrough for the passage of fuel, said passage communicating with the fuel bowl, a vertically positioned and rotatably mounted member located in the fuel bowl and interposed at its lower end in the fuel passage to the nozzle member and having means for controlling the amount of fuel passage with rotation of the member, said member being bored lengthwise nearly to its upper end and having a lateral opening through its upper end to the opening bored in the member, and a passage leading from the said outlet to the upper end of the member with which said opening may be brought into conjunction on turning the member substantially ninety degrees from its normal nearest closed position.

5. A construction containing the elements in combination defined in claim 4, said member having a small opening through its side a short distance below the upper end thereof and above the fuel level in the fuel bowl.

In testimony whereof I affix my signature.

WARD T. SIMPSON.
